(57) **CLAIM**

The ornamental design for a multifunctional footrest as shown and described.

DESCRIPTION

FIG. 1 is a front, left, top perspective view of a multifunctional footrest showing my new design;
FIG. 2 is a rear, right, bottom perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is an enlarged view of portion 9 shown in FIG. 1;
FIG. 10 is an enlarged view of portion 10 shown in FIG. 3;
FIG. 11 is an enlarged view of portion 11 shown in FIG. 3;
FIG. 12 is an enlarged view of portion 12 shown in FIG. 3;
FIG. 13 is an enlarged view of portion 13 shown in FIG. 4;
FIG. 14 is an enlarged view of portion 14 shown in FIG. 7;
and,
FIG. 15 is an enlarged view of portion 15 shown in FIG. 8.
The broken lines in the drawings depict the boundary of the enlargements of the multifunctional footrest that form no part of the claimed design.

1 Claim, 15 Drawing Sheets
